FIG. 4.

UNITED STATES PATENT OFFICE

2,132,989

VANITY BOX

George Sterling McDonald, San Pedro, Calif.

Application September 27, 1937, Serial No. 165,966

2 Claims. (CL 132—83)

This invention relates to a vanity box, one of the objects being to provide an attractive compact device of this character in which cosmetics or the like can be stored readily.

5 A further object is to provide a novel arrangement of compartments and lids therefor, one of the lids constituting a protecting means for a mirror carried by the lid of another compartment when the latter compartment is in normal position.

10 A further object is to provide a vanity box having foldable supporting legs whereby the device can be stored readily in a small space when not in use.

15 With the foregoing and other objects in view which will appear as the description proceeds, the invention consists of certain novel details of construction and combinations of parts hereinafter more fully described and pointed out in 20 the claims, it being understood that changes may be made in the construction and arrangement of parts without departing from the spirit of the invention as claimed.

25 In the accompanying drawings the preferred form of the invention has been shown.

In said drawings

Figure 1 is a plan view of the vanity box, a portion being broken away.

Figure 2 is a side elevation.

30 Figure 3 is a view partly in front elevation and partly in section showing the outer lid open.

Figure 4 is a section on line 4—4, Figure 1.

35 Referring to the figures by characters of reference 1 designates the body of the case which preferably is shaped to approximate the appearance of a grand piano. This case is provided with hinged legs 2 having any suitable means, such as hooks 3 for holding them against folding.

40 The top of the casing 1 has a lid 4 hingedly mounted along one side as shown at 5 so that it can be swung upwardly to expose a compartment 6 formed in the back portion of the casing and a second compartment 7 formed in the front portion of the casing, the two compartments being 45 separated by a partition 8. Compartment 7 is open at the front as well as the top but the front is adapted to be closed by a hinged leaf 9 connected to the front edge portion of the lid or cover 4, there being recesses or openings 10 in the sides of the casing 1 at the forward end thereof whereby the fingers of the user can be inserted back of leaf 9 for the purpose of swinging it upwardly to open position and relative to the lid or cover 4.

55 Slidably mounted within the front compartment

1 is a drawer 11 the bottom 12 of which is extended forwardly as at 13 to support blocks 14 on which is mounted an imitation piano keyboard 15. This keyboard 15 and the forward end of the bottom extension 13 provide a space 16 closed 5 at the front by a facing strip 17 from which a knob 18 or the like is extended. The space 16 opens into the main compartment 19 in the drawer 11 and this latter compartment is normally closed by a hinged lid 20. This lid is 10 below and spaced from the lid or cover 4 and carries a hinged leaf 21 normally resting on a cushioning member 22 and carrying a mirrored surface which is lowermost when the leaf is folded onto the cover as shown in Figure 4.

15 When leaf 9 is in closed position it extends downwardly to the finishing strip 17 so as to conceal the imitation keyboard. When the leaf 9 is swung upwardly and backwardly onto the lid or cover 4 it fully exposes the front of the drawer 20 and said drawer thus can be slid forwardly from within compartment 7 so as to expose leaf 21 which thereafter can be swung upwardly to the position shown in Figure 3 so as to be used as a mirror.

25 The lid 20 of drawer 11 cannot be raised, however, without fully raising the lid or cover 4 which, under some conditions, can be supported in a partly raised position by a hinged brace or strut 23 mounted in casing 1 as shown in Figure 30 3 thereby forming a light shield for protecting the mirror from glare. For the purpose of completely opening lid 20, the cover 4 must be fully raised, as will be obvious.

35 The extension space 16 provides a secret compartment accessible only from within the compartment 19. Lid or cover 4 affords ample protection for the mirrored leaf 21 and by opening this lid or cover 4 access can be had readily to the contents of the back compartment 6.

40 This article constitutes an attractive vanity box because of its simulation on a small scale of a grand piano. It can be made of wood, metal or any other suitable material and constitutes a desirable accessory for a dressing table.

45 It will be noted that the forwardly extended portion of the drawer 11 simulating a keyboard, constitutes a ledge on which various articles may be placed temporarily and the leaf 9 not only serves to cover and conceal this ledge but also 50 constitutes a gravity means for retaining the drawer within casing 1 so that it will not slide inadvertently out of position in the case.

What is claimed is:

1. A vanity box including a case having a com- 55

partment therein, a drawer slidably mounted in and adapted to be withdrawn from the compartment, said drawer having a forwardly extended portion containing an extension of the compartment, a lid hingedly connected to the top of the drawer, a mirror hingedly mounted on said lid and movable into an upstanding position thereon, a lid hingedly connected to one side of the case, means for supporting said lid in an upwardly extending position to overlie and shield the mirror when in upstanding position on the drawer lid.

5 10 2. A vanity box including a case, a drawer slid-

ably mounted therein and having a hollow front ledge opening into the drawer, a lid hingedly connected to the back of and normally closing the drawer at the top, a mirror movably mounted on the outer surface of said lid and movable into or out of upstanding position thereon, a cover hingedly connected to the case and normally overlying the drawer and mirror, and means for supporting said cover in an upwardly extending position, there being a clearance between the elevated cover and the lid to permit the mirror to extend upwardly therebetween.

5 10 15 GEORGE STERLING McDONALD.
